UNITED STATES PATENT OFFICE.

PAUL MAUSER, DECEASED, LATE OF OBERNDORF-ON-THE-NECKAR, GERMANY, BY
FRIEDRICH EICHHORN, ADMINISTRATOR, OF OBERNDORF-ON-THE-NECKAR,
GERMANY, ASSIGNOR TO WAFFENFABRIK MAUSER AKTIENGESELLSCHAFT, OF
OBERNDORF-ON-THE-NECKAR, GERMANY, A CORPORATION OF GERMANY.

MEANS FOR COMBINING THE BARREL WITH THE RECEIVER IN CONNECTION WITH FIREARMS.

1,234,783.

Specification of Letters Patent. Patented July 31, 1917.

Application filed December 1, 1914. Serial No. 875,050.

To all whom it may concern:

Be it known that PAUL MAUSER, deceased, late a subject of the King of Wurttemberg, and residing at Oberndorf-on-the-Neckar, in 5 the Kingdom of Wurttemberg, Germany, invented certain new and useful Improvements in Means for Combining the Barrels with the Receivers in Connection with Firearms, of which the following is a specification.

- 10 This invention relates especially to automatic loading fire arms and has for its object to render the barrel readily interchangeable, to simplify and cheapen the manufacture of the barrel and the cartridge 15 chamber, which is of great advantage especially for automatic loading fire arms inasmuch as it is thus possible to more easily extract the discharged cartridge shells without the aid of a lubricant. As compared 20 with the arrangements hitherto in use, wherein the barrel is integral with its end portion carrying the cartridge chamber and the locking abutments and is screwed with the said end portion into the so-called sleeve 25 head of the receiver, the aforesaid advantages are attained by inserting an intermediate piece between the barrel proper *i. e.*, the projectile guiding part possessing the 30 grooves, and the sleeve head of the receiver, which intermediate piece contains the cartridge chamber as well as the locking abutments separately, and extends into the sleeve 35 head on the one hand and receives the rear end of the barrel on the other hand.

- 40 A constructional form of the invention is shown by way of example in the accompanying drawings.

Figure 1 shows the respective parts of the fire arm in longitudinal elevation and partly in section.

Fig. 2 is a longitudinal section of the intermediate piece and

Fig. 3 is an end elevation thereof.

The constructional form as shown is 45 adapted for an automatic fire arm with ro-

tatable breech bolt, wherein the locking takes place by the co-operation of spiral nipples with correspondingly shaped grooves and shoulders directly in rear of the cartridge chamber. According to the invention, the 50 cartridge chamber is arranged, like the said locking or gripping shoulders, in the special dividing piece *m*, which is screwed with its rearward end in the sleeve head *i* of the receiver *h* and is provided at its front end 55 with an internal thread, in which the rear end of the barrel *l* is screwed. The separation is effected in the construction shown in such a manner that the piece *m* receives the cartridge shell with a part of its collar, 60 while the front part of the cartridge collar extends with the projectile into the barrel proper. The connecting surfaces are beveled at both ends of the dividing piece as well as at the rear end of the barrel in order to insure a very wide, secure and tight joint.

It is obvious that the invention is also adapted for hand loading fire arms as well as for automatic loading fire arms. The advantages attained by the invention are 70 readily obvious, so that no further explanation in that respect is necessary. It may however be stated that on the one hand the interchanging of barrels worn out by shooting or barrels damaged otherwise, is considerably facilitated and cheapened, because it is only necessary to replace the projectile guiding part, while, on the other hand, if the cartridge chamber or the locking abutments are damaged, the projectile guiding part 80 can be retained and only the dividing piece need be replaced.

What is claimed is:—

1. A fire arm comprising a receiver, a barrel proper, and an intermediate part having a cartridge chamber therein and locking lugs for a breech bolt, and interengaging means between said intermediate part and said barrel proper and said receiver.

2. A fire arm comprising a receiver, a bar-

rel proper and an intermediate part, said receiver having a sleeve adapted to receive one end of said intermediate part, said intermediate part having at its other end a 5 sleeve adapted to receive the rear end of the barrel proper, said intermediate part also having therein a cartridge chamber and locking lugs for a breech bolt.

In witness whereof, I have hereunto

signed my name in the presence of two sub- 10
scribing witnesses.

FRIEDRICH EICHHORN,
*Administrator of the estate of Paul Mauser,
deceased.*
